UNITED STATES PATENT OFFICE

HEINRICH BREITWIESER, OF GRIESHEIM NEAR DARMSTADT, GERMANY, ASSIGNOR
TO MASCHINENFABRIK AUGSBURG-NURNBERG, A. G., OF NUREMBERG, GERMANY, A
CORPORATION OF GERMANY

ECCENTRIC LIFTING DEVICE

Application filed May 18, 1931, Serial No. 538,061, and in Germany May 21, 1930.

This invention relates to an eccentric lifting device, especially for use in connection with the ends of pivot bridges. It is an improvement of such devices of the type illustrated in U. S. Patent No. 1,807,780 in which two eccentric disks are movable along horizontal path and act as bearings for a supporting roller arranged between them, which roller moves upwardly upon rotation 10 of said discs during the power stroke of actuating means for the device and takes up the load. The general object of this improvement is to relieve the lifting device, particularly the eccentric and lifting disks thereof, of load while the bridge is in operative position, in a more advantageous manner than hitherto.

According to the construction disclosed by the aforesaid patent the relief is effected by lowering the lifting disk a little from its highest position so as to place it down upon a supporting member arranged between the running paths, and by lifting the running disks off their running paths so that the entire 25 load rests upon said supporting member.

It has, however, been found that, owing to the elastic changes of the shape in the material when the lifting disks are seated upon the supporting member, the operation of the 30 gear is accompanied by strong frictional resistances which entail detrimental effects in the course of time. More particularly, therefore, the object of the present invention is to obviate the detrimental effects, mentioned by 35 the provision of a supporting member which is separate from the lifting disk and which, in the normal position of the bridge end, supports the load thereof and thereby relieves the remaining parts of the device of load. I 40 attain this object by the provision of a supporting member which is movably supported by and extends below the lifting disk and is urged by a spring against the front wall of a downwardly widening slot, in the lifting 45 disk so that upon movement of the lifting disk in a direction to lift the bridge end and upon engagement of the lower end of the supporting member with a suitable stop, continued movement of the lifting disk with the 50 running disks, permitted by the downwardly

widening slot, results in the load being transferred to the supporting member.

The advantage thereby attained is this that when the lifting disk or the support located in its slot is lowered only a slight friction, 55 caused by the pull of the spring, and taking place between the abutment member of the supporting bearing and said support occurs, the support becoming stationary upon a suitable bearing when it has seated down 60 thereon so that on the continued movement of the lifting disk and when the running disks are lifted no friction whatever of the parts subjected to the load of the bridge arises.

The invention is illustrated diagrammatically and by way of example on the accompanying drawing on which Figure 1 is a side-view, partly in vertical section, of the lifting device, Figure 2 is a plan of the eccentric mechanism. Figure 3 is a frontal view of 70 this mechanism, seen from the lefthand disk with its slot. And Figs. 4-7 are vertical sections through the lifting disk with its slot, and of some adjacent members, together with side-views of the supporting member 75 located in said slot, these parts being shown in several positions, all as more fully described hereinafter.

At *a* are shown two circular running disks having eccentrically arranged circular bores 80 provided with suitable bearings *b* through which pass the trunnions *c* of a lifting disk *d* disposed between said running disks. Pins *p* disposed in bearing eyes *q* of the running disks *a* are engaged by thrust rods *r* connected with a suitable driving device as illustrated, for example, in the aforementioned U. S. Patent 1,807,780, and by means of said rods the running disks may be caused to roll in one direction or the other over tracks or 90 paths *e* which are slightly inclined downwardly towards the driving device. On the inner faces of the disks *a* are rims *a'* for guiding said disks on the tracks *e*, while toothed sectors *a''* on said disks mesh with 95 racks *s* on the tracks *e* to positively assure movement of the disks along the tracks when the disks are rotated.

The lifting disk *d* is provided a practically vertical slot *f* that is downwardly enlarged, 100

as shown in Figs. 4-7. In this slot is arranged a supporting member *g*, which, near its lower end, carries lateral rollers *h* (Figs. 1-3) bearing upon ledges *i* affixed to the disk *d*. Connected to the supporting member *g* adjacent to the rollers *h*, are arms *k* of two toggle-joint levers *k*, *l*. The arms *l* of these levers are crooked, as shown in Fig. 1, and their other, i. e. upper ends are connected 10 with the disk *d*. The arrangement and combination of these parts appear particularly distinct from Fig. 1. The two lever arms *l* are connected with one another by a transverse member *l'*, which is subjected to the 15 pressure of a helical spring *m* which is preferably guided by a bolt extending forth from said transverse member *l'*, as shown in Fig. 1. The other end of the spring bears upon the lifting disk *d*. Owing to the arrangement 20 and combination of these parts the spring *m* tends continually to draw the supporting member *g* towards the lefthand (with respect to Figs. 1 and 4-7) wall of the slot *f*, as well as to turn the disk *d* in the opposite direction. The arrows in Figs. 4-7 indicate the direction of action of the spring with 25 respect to the member *g*.

Between the running members *e* is located a stationary block *n* provided with an abutment *o* which when the lifting disk *d* is moved upwardly is located in the path of the lower end of the supporting member *g* which projects forth from the lower end of the slot *f*. In this position of these parts the upper end 30 of the member *g* lies flush with the upper end of said slot.

When the rolls *a*, *a*, are moved from the right to the left, the supporting member *g* is first moved downwardly so as to contact with the block *n*, and then to the left (as indicated by the above-mentioned arrows) so that its end contacts with the abutment *o*, as in Fig. 5. If, when the parts are in this position, the disks *a* and *d* are further turned, the disk *d* 40 will be lowered, as will be also the supporting member *g*, and this latter will then bear upon the block *n*, as in Fig. 6. The disk *d* proceeds, however, in its rotary motion under the action of the spring *m* also as in Fig. 6, and when now the after-movement of the gearing takes place, the disk *d* is drawn off from the bridge, as in Fig. 7, the righthand side of the slot *f* contacting now with the member *g*. Thus, the member *g* transmits 45 the entire traffic load upon the block *n*, or upon the foundation respectively, whereas the lifting mechanism is relieved therefrom.

I claim:

60 An eccentric lifting device, especially for use in connection with the ends of pivot bridges, comprising, in combination a lifting disk having a practically vertical slot increasing in width from above to below; a 65 supporting member extending through said

slot and projecting forth from the same at the lower end of the same; a spring so arranged as to tend to draw said supporting member towards one of the faces of the slot; a stationary block located below the supporting member, and a projection extending from said block and being so located as to be adapted to constitute an abutment for the projecting end of the said supporting member, substantially as set forth. 75

In testimony whereof I affix my signature. 80
HEINRICH BREITWIESER.
